SOLENOID

Hubert T. Sparrow, Minneapolis, Minn., assignor
to Minneapolis-Honeywell Regulator Company,
Minneapolis, Minn., a corporation of Delaware

Application July 2, 1942, Serial No. 449,461

14 Claims. (Cl. 175—335)

This invention relates to a relatively light, powerful and compact solenoid that is both efficient and positive in operation. In particular, the invention relates to a solenoid for the positive operation of various types of devices under adverse conditions, including the existence of considerable vibration, and the device of the invention is especially adapted for use with aircraft.

An object of the invention is the provision of a switch in which the motion of a switch operating member is transmitted to a dielectric fluid for the hydraulic operation of a switching mechanism and in which the contact members of the switching mechanism are mounted in the dielectric hydraulic fluid.

A further object of the invention is to provide for the operation by an electromagnet of a hydraulically actuated switch and in the provision of means for restricting the flow of the hydraulic fluid to provide a predetermined time delay in the operation of the switch following each initial operation of the electromagnet.

A particular object of the invention is the provision of a solenoid having an armature for the operation of a device and also for the operation of a switch together with the provision of a timing mechanism for operating the switch at a predetermined period following each initial energization of the armature in combination with means providing for the rapid operation of the switch following each deenergization of the solenoid and the accompanying operation of the armature.

In greater detail, my invention relates to a solenoid in which a first circuit employing a relatively high current is provided for each initial operation of the solenoid and where upon the lapse of a predetermined period operation of the solenoid is maintained by a second circuit in which the current and power required to operate the solenoid is substantially reduced.

Additional objects, advantages and features of the invention will be apparent by reference to the following detailed description of one application of my invention together with the accompanying drawing and claims.

The drawing illustrates a vertical sectional view, partly diagrammatic, of a solenoid of my invention together with a schematic illustration of the circuit employed.

In the drawing, the solenoid includes a casing 5 of magnetic material to which is threaded a core and stop member 6. A magnetic sleeve member 7 is also threaded to the casing member

5, and supported upon the stop member 6 is a cylindrical sleeve member 8 of non-magnetic material. An armature 12 is mounted for movement within the cylindrical sleeve member 8 and, as illustrated, is in the deenergized position supported upon the non-magnetic base member 14. Coils 16 and 17 surround the non-magnetic sleeve member 8 and are mounted between the stop member 6 and the sleeve member 7.

An annular opening 20 is formed axially in the upper surface of the stop member 6 and an annular member 21 cooperates with the top of the stop member for securing a diaphragm 22 across the top of opening 20. The diaphragm 22 may be of any suitable kind although I preferably employ a crimped metallic material. A plate member 25 is secured to the disk 21 and together with the diaphragm 22 these members define a chamber 26. Mounted upon the plate 25 is a further annular member 28 of insulating material upon which is secured a diaphragm 30. The diaphragm 30 is of a crimped metallic material and forms a portion of the electrical circuit as hereinafter described. The plate 25, disk 28 and diaphragm 30 define a chamber 31. A cover member 32 provided with openings 33, is placed on top of diaphragm 30 so that this diaphragm is secured between cover member 22 and annular member 28. A passageway 34 is formed in the plate 28 for communication with the chamber 31 and this passageway communicates with a threaded opening 35 in cover member 32. This opening is closed off by a plug member 36.

The chamber 26 communicates with the chamber 31 through one or more orifice members 40 formed in the plate 25. A relatively large opening 41 is also provided in the plate 25 and forms a valve seat with which a valve 42 cooperates. The valve 42 is supported by a spring 43. This spring is secured to the plate 25 and serves to normally maintain the valve in the closed position.

A switch contact 44 is mounted upon the plate 25 for cooperation with a second contact 46 that is mounted on the metallic diaphragm 30. A threaded sleeve member 47 is mounted upon the plate 32 and, together with an opening 48 in the plate, forms a passageway in which is mounted a spring 49 for biasing the diaphragm 30 in a direction to close the switch contacts. A screw 50, having a knurled head, is mounted for adjustment within the threaded sleeve member 47 and one end of the biasing spring 49 is engaged by the screw to thus provide for selectively

varying the bias exerted by the spring and metallic diaphragm upon the switch contact 46.

A dielectric and hydraulic fluid is admitted to the communicating chambers 26 and 31 through the passageway 34 and the plug member 36 serves to seal the fluid within the two chambers. It will be noted that when the chambers are supplied with fluid care should preferably be taken to do so in a manner that will insure against the admission of air to the chambers in order to minimize the effects of varying altitudes and temperatures upon the operation of the switch.

The armature 12 has a central passageway 55 formed in the upper end that communicates with an enlarged central passageway 56 also formed in the armature. A piston member 57 is movable within the passage 55 and has an enlarged head portion 58 that is movable within the passageway 56. A spring 59 serves to bias the piston head against the shoulders of the armature that define the passageway 55. The piston 57 extends through a passage 54 formed in the stop member 5 and has a threaded end portion 60 of reduced diameter that is secured to the diaphragm by a nut 61 and washer members 62. Threadedly secured to the lower end of the armature is a member 65 having a head portion 66 to which is secured an attachment member 67 for the operation of a valve, switch or other type of device, not shown. The head 66 of the member 65 serves to support and guide one end of a spring 68, the other end of which bears against the base member 14. This spring 68 is employed to bias the armature member to the deenergized position.

The coil 16 is preferably formed of low resistance wire having relatively few turns and the coil 17 is formed of a relatively large number of turns of high resistance wire. When the solenoid is energized, as by operation of a switch 72, a circuit is initially completed which includes battery 70, a conductor 71, switch 72, a conductor 73, terminal 74, the coil 16, terminal 75, conductor 76, switch contacts 44 and 46, metallic diaphragm 30, plate 32, grounded conductor 77, and conductor 78 for return to the battery 70. Upon the completion of this circuit a relatively large current is established to produce a relatively large magnetomotive force in the magnetic circuit of the solenoid. The magnetic circuit of the solenoid includes the stop member 6, casing member 5, the sleeve member 7, and the armature 12. This magnetomotive force provides for the positive and rapid operation of the armature 12 to the energized position in which the armature contacts the stop member 6. At this time, following the operation of the armature, the piston member 57 is operated by the biasing spring 59 in an upward direction to also provide for the movement of the diaphragm 22 in an upward direction. The hydraulic fluid contained in the chamber 26 accordingly is forced through the orifice flow restricting member 40 to the upper chamber 31. Sufficient fluid is forced from the chamber 26 to the chamber 31 a predetermined period following the operation of the armature to operate the diaphragm 30 in an upward direction for opening the switch contacts 44 and 46. The time required for the fluid to open the switch contacts 44 and 46 is largely determined by the orifice member or members 40 and may also be varied by adjustment of the diaphragm biasing spring 49.

The opening operation of the switch contacts 44 and 46 serves to remove a shunt from around coil 17 to establish the following circuit: battery 70, conductor 71, switch 72, conductor 73, terminal

74, coil 16, the common terminal 75 for the coils 16 and 17, terminal 82 of the coil 17, conductor 83, and the grounded conductor 78 back to the battery 70. The completion of this circuit which includes each of the coils 16 and 17 serves to increase the resistance inserted in the circuit to provide for a reduction in current and the corresponding reduction in power required for the continued operation of the solenoid.

10 When the solenoid is deenergized by operation of the switch 72, the armature 12 is rapidly returned to the position illustrated in the drawing by operation of the biasing spring 68 and by the force of gravity. This operation of the armature 15 serves to rapidly move the piston 57 and diaphragm 22 in a downward direction. Rapid movement in the downward direction takes place since the fluid returning to the chamber 26 is permitted to flow not only through the orifice 40, 20 but also through the opening 41 which is normally closed by operation of the biased valve 42. The valve 42 is opened in response to the increased differential in pressure between the fluid in the two chambers by reason of the downward operation 25 of the diaphragm.

It is accordingly apparent that in the initial energization of the solenoid, a relatively large magnetic force is established to provide for the rapid and positive operation of the armature. 30 This force is continued for a predetermined period after which the switch contacts 44 and 46 are operated to alter the solenoid circuit and decrease the power required for maintaining the solenoid in its energized or operating position. 35 Upon deenergization of the solenoid it is also apparent that the valve member 42 operates to remove any substantial restriction to the flow of fluid between the chambers 31 and 26 and to thus provide for the rapid closure of the switch contacts 44 and 46 and the rapid downward movement of the armature 12.

In the operation of my switch, it will be observed that the adjustable biasing spring 49 may be omitted where a metallic diaphragm is employed that is otherwise capable of operation in a satisfactory manner, and also that diaphragms may be selected which will be more or less rapid in the operation of the switch contacts.

50 Provision is made for the automatic compensation of the switch of my invention for changes in ambient pressure or altitude by subjecting one side of each of the diaphragms 22 and 30 to the ambient conditions in conjunction with the substantial exclusion of air from the fluid chambers. 55 In addition, the hydraulic fluid employed in the chambers 26 and 31 is preferably of a type in which the temperature characteristics are such as to insure the proper operation of the switching mechanism throughout the relatively very wide range of temperatures to which the solenoid may be subjected.

60 It will be apparent that the electromagnetically actuated hydraulic switch of my invention is susceptible of various embodiments. Thus, embodiments of the switch may be employed for the control of various types of circuits and the flow restricting timing means may be employed for both the switch opening and the switch closing operations or, if desired, the timing means may be dispensed with to provide for the rapid opening and closing operations of the hydraulically actuated switch. The invention is accordingly to be defined within the spirit and scope 65 of the appended claims.

I claim as my invention:

1. In an electromagnetic device, in combination, an electromagnet, an armature, a load operated thereby and means including timing means for decreasing the current flow through the energizing means of the electromagnet at a predetermined period following each initial energization of such means and operation of the armature to its fully attracted position.
2. In an electromagnetic device, in combination, an electromagnet including an armature and energizing means, means including timing means for decreasing the current flow through the energizing means of the electromagnet at a predetermined period following each initial energization of the energizing means and operation of the armature to its fully attracted position, and means operative simultaneously with the de-energization of the energizing means and armature to rapidly provide for the subsequent energization of the energizing means and armature at the original current flow.
3. In an electromagnetic device, in combination, electromagnetic means including an armature and a winding, means including hydraulically operated timing means for decreasing the current flow through the energizing winding of the electromagnetic means at a predetermined period following the energization of the winding and consequent operation of the armature, and means simultaneously operative with the deenergization of the winding to rapidly provide for the subsequent energization of the winding at the original rate.
4. In combination, a solenoid, a first circuit for the relatively high supply of power to initially energize the solenoid, a second circuit for maintaining the energization of the solenoid, a switch for transferring the control of the solenoid from the first circuit to the second circuit, timer means for delaying the operation of the switch for a predetermined period following each initial energization of the solenoid, and means for the rapid operation of the switch to its original position upon deenergization of the solenoid.
5. In combination, a solenoid, a circuit for the supply of power to initially operate the solenoid in a rapid and positive manner, a circuit for maintaining energization of the solenoid, a switch actuated by the solenoid for transferring energization of the solenoid from the first circuit to the second circuit, and time delay means for assuring the positive initial operation of the solenoid by the first circuit before operation of the switch for transferring the operation of the solenoid to the said second circuit.
6. In combination, a first circuit and a second circuit, a switch for controlling said circuits, electromagnetic actuating means included in each of said circuits for controlling an armature, a switch operated upon movement of the armature, and means for causing a time delay between operation of the armature to its fully attracted position by the electromagnetic means and the operation of the switch.
7. In combination, a solenoid, an armature, a switch, a first circuit of relatively high power for initially energizing the solenoid, a second circuit of relatively low power for maintaining the energization of the solenoid, and time delay switch operating means for transferring the control of the solenoid from the first circuit to the second circuit after movement of the armature to its fully attracted position.
8. In combination, a main circuit and a main
9. In combination, a hydraulic chamber and a first diaphragm forming a part thereof, a second hydraulic chamber and a second diaphragm forming a part thereof, a fluid in said chambers, switch means actuated by the said first diaphragm, orifice means between the first and second chambers for restricting the flow of fluid between the first and second chambers, and means moving the second diaphragm to control the fluid in the first and second chambers to operate the switch.
10. In combination, a first hydraulic chamber and a first diaphragm forming a part thereof, a second hydraulic chamber and a second diaphragm forming a part thereof, switch means actuated by the said first diaphragm, means including orifice means between the first and second chambers for restricting the flow of fluid between the first and second chambers, plunger means for operating the second diaphragm to control the fluid in the first and second chambers for operating the switch, electromagnetic means for actuating the plunger including an armature having a chamber within which one end of the plunger means is movable, means within the armature chamber for biasing the plunger, means for movement in a direction for operating the said second diaphragm and switch in a first manner at a predetermined period following each initial energization of the electromagnetic means, said armature including means for the rapid operation of the plunger and second diaphragm in a second manner when the electromagnetic means is deenergized, and means providing for the substantially unrestricted flow of fluid from the first hydraulic chamber to the second hydraulic chamber when the armature and electromagnetic means are deenergized for the rapid operation of the switch in a second manner.
11. In an electromagnetic device, in combination, electromagnetic means including an armature and a winding, hydraulically operated time delay means for decreasing the current flow through the energizing winding of the electromagnetic means at a predetermined period following actuation of said time delay means, and means operated by said armature upon movement to its actuated position for actuating said time delay means.
12. In combination, a solenoid, a first circuit for the relatively high supply of power to initially energize the solenoid, a second circuit for maintaining the energization of the solenoid, a switch for transferring the control of the solenoid from the first circuit to the second circuit, hydraulically operated timer means for delaying the operation of the switch for a predetermined period following the initial energization of the solenoid, and means for the rapid operation of the switch to its original position upon deenergization of the solenoid.
13. In combination, a solenoid, an armature actuated thereby, a first circuit for the relatively high supply of power to initially energize the solenoid, a second circuit for maintaining the energization of the solenoid, a switch for transferring

the control of the solenoid from the first circuit to the second circuit, hydraulically operated timer means including a first chamber and a first diaphragm, a second chamber and a second diaphragm, a fluid in said chambers, orifice means between the first and second chambers for restricting the flow of fluid between the first and second chambers, connections between said armature and the first diaphragm for flowing fluid from the first chamber to the second chamber to move the second diaphragm to operate the switch for transferring the control of the solenoid from the first circuit to the second circuit upon attraction of said armature.

14. In combination, a solenoid, an armature actuated thereby, a first circuit for the relatively high supply of power to initially energize the solenoid, a second circuit for maintaining the energization of the solenoid, a switch for transferring

the control of the solenoid from the first circuit to the second circuit, hydraulically operated timer means including a first chamber and a first diaphragm connected to said armature for actuation thereby when attracted to said solenoid, a second chamber and a second diaphragm, a fluid in said chambers, orifice means between the first and second chambers for restricting the flow of fluid between the first and second chambers upon actuation of the first diaphragm by the armature for flowing fluid from the first chamber to the second chamber to move the second diaphragm for operating the switch and transferring the control of the solenoid from the first circuit to the second circuit, and means for the rapid operation of the switch to its original position upon deenergization of the solenoid.
